UNITED STATES PATENT OFFICE

162,197

WHEEL COVER

George Albert Lyon, Detroit, Mich.

Application April 5, 1950, Serial No. 8,993

Term of patent 14 years

(Cl. D14—30)

To all whom it may concern:

Be it known that I, George Albert Lyon, a citizen of the United States and a resident of the city of Detroit, in the county of Wayne and State of Michigan, have invented a new, original, and ornamental Design for a Wheel Cover, of which the following is a specification, reference being had to the accompanying drawing, forming a part thereof.

On the drawing:

Figure 1 is a side elevational view of my novel design for a wheel cover;

Figure 2 is a profile view showing the cross sectional contour of the cover of Figure 1; and

Figure 3 is a fragmentary side perspective view of the cover.

The dotted lines in Figures 1 and 2 showing the conventional tire and wheel assembly are for illustrative purposes only.

I claim:

The ornamental design for a wheel cover, substantially as shown and described.

GEORGE ALBERT LYON.
